THEFT-PROOF BOTTLE CONTAINER
Robert M. Bailey, 1805 Radford St.,
El Paso, Tex. 79903
Filed July 1, 1966, Ser. No. 562,308
14 Claims. (Cl. 211—74)

This invention relates to a container for receiving bottles and for preventing unauthorized removal of bottles from the container. In particular, this invention contemplates a rack for a plurality of bottles which may be installed in a commercial establishment whereby a plurality of bottles may be inserted in the bottle rack at will by any person but once inserted will be locked in the container to prevent the unauthorized removal of the bottles therefrom. Such containers may also have application and utility for receiving milk bottles and the like in homes and other establishments.

An object of this invention is the provision of a container for preventing the unauthorized removal of bottles therefrom.

Another object of this invention is the provision of a container for easily receiving a plurality of bottles and for preventing the unauthorized removal of the bottles from the container.

Yet another object of this invention is the provision of a novel and simple lock mechanism for preventing the unauthorized removal of bottles from the container.

An additional object of this invention is the provision of a novel trip mechanism for locking bottles in place in a container.

Other objects of this invention will appear from the following specification and the drawings to which reference is now made.

FIGURE 1 is a front view of the cover of the container of this invention showing a plurality of bottle-receiving apertures.

FIGURE 2 is a side view of a single aperture and its associated lock mechanism shown in partial cross-section taken substantially along line 2—2 in the direction of the arrows as shown in FIGURE 1.

FIGURE 3 is a side view of the lock mechanism taken from substantially the same view as FIGURE 2 but showing the mechanism in its locked position.

FIGURE 4 is a view of the inside of the cover showing portions of the lock mechanism taken substantially along line 4—4 in the direction of the arrows as shown in FIGURE 2.

FIGURE 5 is a top view of the lock mechanism of this invention.

Reference is made now to FIGURE 1 which shows the front cover 10 of the container of this invention. The side and rear surfaces may be of conventional construction and are not shown for purposes of clarity. Included in cover 10 may be one or more apertures 12 for receiving a bottle. Preferably, the cover 10 may be hinged by one or more hinges 14 to permit its movement to permit access to the bottles and the lock mechanism. Of course, other forms of movement may be provided. For example, it would be possible simply to secure the cover over the sides of the container and to lift the cover therefrom.

Referring now to FIGURES 2, 3, 4 and 5, the lock mechanism of this invention includes a locking plate 16 which is preferably slidably mounted by a plurality of guides 18 and 20 to the inside of the front cover 10 to permit its reciprocal motion from its locked to its unlocked position. Locking cover 16 may include a plurality of pins or projections 22 and 24 which facilitate the locking and unlocking motion of the locking cover plate 16 as will be described. A stop 26 is provided at

2

the bottom of the locking plate 16 to limit its downward movement.

Lock means are provided for maintaining the locking plate in its locking position in which it covers at least a portion of the bottle receiving aperture when it is moved to its locking position by a mechanism to be described hereinafter. The locking mechanism is best shown in FIGURES 2 and 3 and comprises a bolt 28 which is biased toward cover 16 by a spring 30 and is slidably received in a barrel 32 which is in turn supported by an upright support 34 secured to a plate 36. Plate 36 may be secured by a plurality of pins 38 and 40 to a support base 42 which is in turn supported by a plurality of cross bars 44 and 46. The cross bars 44 and 46 may support a plurality of such support bases in a row corresponding to a row of bottle receiving apertures. Support base 42 includes upright sides 48 and 50. An operator knob 52 may be provided for manual operation of bolt 28 if desired. It will be apparent from the drawings that when the locking plate 16 is in the unlocked position, as shown in FIGURE 2, the bolt 28 is biased toward the cover plate 10 and rests against locking plate 16 in the manner shown. As the locking plate 16 is moved upwardly the bolt 28 will move under the bottom edge of the locking plate 16 to maintain locking plate 16 in the locked position. It will also be apparent that when the cover 10 is opened, for example as pivoted on hinges 14, the locking plate 16 is moved away from bolt 28 permitting locking plate 16 to slide down to its unlocked position. Thus, removal or opening of cover 10 automatically returns all the locking plates to their unlocked position.

Movement of locking plate 16 from its unlocked position, as shown in FIGURE 2, to its locked position, as shown in FIGURE 3, is accomplished by a pivoted member or trip pedal 54 which carries on the end thereof an engaging wire or member 56 which selectively engages pins 22 and 24 on locking cover 16. Pedal 54 is pivoted by a pin 58 at a point between the ends thereof. In the preferred embodiment a bias spring 60, best shown in FIGURE 4, biases the proximate end of the pedal 54 to which the engaging means 56 is attached in the downward direction thus resisting any depressing movement of the distal end of pedal 54. When a bottle is inserted in the aperture 12, however, the weight of the bottle depresses the distal end of pedal 54 against the bias force of spring 60. As the distal end of pedal 54 is depressed the pedal pivots about ends 58 moving engaging wire 56, which is in engagement with pins 22 and 24, in the upward direction, thereby moving locking plate 16 to its locked position where it is secured by bolt 28 as previously described. It will be understood, of course, that it is not necessary that the weight of the bottle actuate pedal 54. The mere insertion of the bottle may, if desired, be caused to depress the distal end of pedal 54 to lock the bottle in the container.

Bias spring 60, or any other desired bias means such as weights, etc., serves two functions. First, it prevents pivotal movement of pedal 54 thereby preventing movement of pedal 54 to its locked position and consequently movement of locking plate 16 to its locked position at all times except when a bottle is inserted in the aperture 12. Secondly, bias spring 60 causes pedal 54 automatically to return to its unlocked position upon removal of the bottle from contact therewith. It will thus be seen that upon opening of the cover of the container of this invention all the locking plates are automatically reset and by removal of the bottles from the container, all the locking mechanisms are automatically reset. Upon closure of the cover, the bolts 28 will again rest against locking plate 16 in the manner shown in FIGURE 2.

A container, which is preferably made of metal such as steel or aluminum, has been described and illustrated in the drawings which accomplishes the objects of the invention set out hereinbefore. The utility and convenience of the invention will be apparent from its simplicity, dependability of operation, and its economy in construction. While the primary object of this invention is the provision of a container for a plurality of bottles, it will be realized that a single bottle container incorporating the inventive locking concept may be provided for home use. For example, such a container may be secured in or near the entrance to a home for reception of a bottle or a plurality of bottles to be placed there by the milkman. The cover to the container may be locked by any conventional locking means and the key may be in the possession only of the owner of the premises. Thus, only by opening the cover of the container may the bottles be removed therefrom. This will effectively prevent theft of bottles and like containers.

It is contemplated that this invention will find its primary utility in application in commercial establishments, however. A significant problem exists in such establishments which are provided with vending machines to dispense soft drinks or other beverages in bottles or similar containers. Frequently there is a deposit required for the removal of bottles from the premises and in such establishments bottles are rarely removed from the premises by the persons working there. However, when the empty bottles are placed in racks it is not infrequent that individuals may steal the bottles from the racks and take them to stores or other commercial establishments to receive the deposit on the bottles. The provision of one or more racks of the type described herein will effectively prevent theft of the bottles in this manner.

While the invention has been described with reference to particular mechanisms and to specific embodiments, it is intended that these embodiments and mechanisms be included merely as exemplary of the invention and not in a limiting sense. Obvious changes in particular constructional details, the specific nature of certain of the individual operating mechanisms, and similar features may be made by persons skilled in the art without departing from the spirit of the invention. The invention is intended to be limited only by the appended claims.

I claim:

1. A theft-proof bottle container comprising a cover including therein an aperture for receiving a bottle, a locking plate for selectively covering at least part of the aperture to prevent removal of the bottle, lock means for maintaining the locking plate in a position covering at least part of the aperture, and bottle actuatable trip means for moving the locking plate to its locked position covering at least part of the bottle receiving aperture in response to the insertion of a bottle in the aperture.

2. The invention of claim 1 further including guide means secured to the inside of the cover and wherein the locking plate is received in the guide means for slidable movement between its unlocked and its locked positions.

3. The invention of claim 1 wherein the lock means comprises a member biased toward the locking plate for automatically moving under the lower edge thereof when the locking plate is moved to its locked position.

4. The invention of claim 1 wherein the bottle actuatable trip means comprises a pivoted member and engaging means on the proximate end of the pivoted member for engaging and moving the locking plate to its locked position when the distal end of the pivoted member moves in response to the insertion of a bottle in the aperture.

5. The invention of claim 4 further including a projection on the locking plate for engagement with the engaging means on the proximate end of the pivoted member.

6. The invention of claim 4 further including bias means for biasing the pivoted member toward the bottom

of the locking plate to prevent movement of the pivoted member to its locked position except when a bottle is inserted in the aperture overcoming the force of the bias means.

7. The invention of claim 4 wherein the pivoted member is caused to move in response to the weight of the bottle.

8. The invention of claim 1 wherein the trip means is actuated by the weight of the bottle.

9. The invention of claim 1 wherein opening of the cover disengages the locking plate from the lock means to permit the locking plate to return to its unlocked position and further including means for returning the trip means to the unlocked position upon removal of the bottle.

10 15 20 25 30 35 40 45 50 55 60 65 70 75 80 85 90 95

19. The invention of claim 4 further including means slidably mounting the locking plate on the inside of the cover to permit the locking plate to disengage the lock means upon opening of the cover and further including means for automatically returning the pivoted member to its open position when the bottle is removed from contact therewith.

11. The invention of claim 1 further including means slidably mounting the locking plate on the inside of the cover, pins projecting inwardly from the locking plate, and wherein the trip means comprises

a trip pedal, pivot means supporting the pedal at a point between the ends thereof, and an engaging member on the proximate end of the pedal for selectively engaging the pins on the locking plate for moving the locking plate to its locked position when the distal end of the trip pedal is depressed by the bottle.

12. The invention of claim 11 further including bias means resisting the depressing action of the bottle on the distal end of the pedal.

13. The invention of claim 1 wherein the bottle container includes a plurality of apertures with the associated locking mechanism included therewith and wherein the bottle actuatable trip means is responsive to the weight of the bottle.

14. The invention of claim 1 including a plurality of apertures in the cover for receiving a plurality of bottles and a locking mechanism associated with each of said apertures further including

means slidably mounting the locking plates on the inside of the cover, a plurality of pins projecting inwardly from each of the locking plates; wherein the lock means comprises

a bolt, and bias means urging the bolt toward the cover to force under the bottom edge of the locking plate to maintain the locking plate in its locked position only while the cover is closed; and wherein the trip means comprises

a trip pedal, pivot means supporting the pedal at a point between the ends thereof,

an engaging member on the proximate end of the trip pedal for selectively engaging the pins on the locking plate for moving the locking plate to its locked position when the distal end of the trip pedal is depressed by the weight of the bottle, and

spring bias means resisting the weight of the bottle.
